UNITED STATES PATENT OFFICE.

JAMES C. MOORE, OF PHILADELPHIA, PENNSYLVANIA.

PYROTECHNIC SIGNAL-ALARM AND BURNING TORCH.

SPECIFICATION forming part of Letters Patent No. 768,065, dated August 23, 1904.

Application filed March 8, 1904. Serial No. 196,275. (No model.)

To all whom it may concern:

Be it known that I, JAMES C. MOORE, a citizen of the United States, residing at the city of Philadelphia, in the county of Philadelphia, 5 and State of Pennsylvania, have invented certain new and useful Improvements in Pyrotechnic Signal-Alarms and Burning Torches, of which the following is a specification.

My invention has relation to a pyrotechnic signal-alarm and burning torch adapted for use as a means of signal or alarm of fire or robbery of edifices or buildings, which device is intended to be suitably arranged outside of the edifice or building and of being actuated 15 from within the edifice or building to give the signal or alarm by a momentary pyrotechnic display and continuing burning torch-light thereafter.

My invention, stated in general terms, consists of a pyrotechnic signal-alarm and burning torch for purposes stated, among others, hereinafter described and claimed.

The nature and characteristic features of my invention will be more fully understood 25 from the following description, taken in connection with the accompanying drawing, forming part hereof, illustrating partly in vertical section and partly in elevation a pyrotechnic signal-alarm and burning torch embodying 30 characteristic main features of my present invention.

Referring to the drawing, A represents the signal-alarm and torch consisting of a base a, through which extends a standard or support 35 a', carrying at the upper end, preferably, flaring or divergent metal sockets b' and b² of the alarm and torch. The standard or support a' is suitably insulated from the body b, integral with the sockets b' and b². Within the sockets 40 b' and b² are snugly fitted metal-faced insulating-plugs c and c', provided with shells or tubing d and d', projecting therefrom and supported by the metal facing c² and c³ of the plugs c and c' from the sockets b' and b². Within the tubing or shell d is provided in the upper and lower portions suitable packing 45 material e and e', and interposed between this packing is introduced easily-ignited pyrotechnic material e². In the shell or tubing d ex-

tends a fuse consisting, preferably, of two 50 metallic strips e³, forming the terminals of an electric circuit by respectively engaging the metal facing c² of the plug and a binding post or screw f, extending through the base of the socket b'. The fuse-strips e³ at their free upper ends are united by a wire e⁴, of metal, adapted to become highly heated when the current passes through the same. In the socket b² the shell or tubing d' is constructed 55 of suitable non-combustible material, within which a suitable slow-burning material g is loosely or otherwise packed, and within the body of the said material is introduced fuse-strips e³, similar to those already described, with their free ends united to a wire e⁴, of 60 metal, adapted to become highly heated to ignite the material g in the shell d' to cause a slow-burning torch to be established. The upper portion of both of the shells d and d' is closed by caps or covers d⁴ and d⁵. These 65 caps are respectively removed or freed from the shells by the effect of an electric current in a manner to be hereinafter more fully explained. In the instance of the torch by an igniting of the easily-ignited pyrotechnic material d², packed in the upper portion of the shell d', the cap d⁴ is forced off, while the cap d⁵ on the shell d and packing e are forced off 70 and out of the shell d by an igniting of the material e² to cause a pyrotechnic display to 75 be given off, as an alarm, while at the same time or immediately thereafter the shell d', with the cap removed, will exhibit simply a slow-burning torch as a means of continuing 80 signal of the hazardous condition of the edifice or building or for whatever purpose the alarm and signal may be used.

B is a source of electric energy, such as a storage battery. From the battery B the line-circuit 10 is from one pole of the battery 90 to a switch i and contact-point i', by the line 11 from the point i' to a binding post or screw i² of the socket b², whence the current passes through the metal portions of the socket b², metal facing c³ of the insulating-plug c', fuse-strips e³ and wire e⁴ of the slow-burning torch d', to the binding post or screw f', line-wire 95 13 and body b, to the socket b', metal facing

*c*² of the plug *c*, fuse-strips *c*³ and wire *c*⁴ of the pyrotechnic signal-alarm *d*, and by the binding-post *f* of the socket *b'* and line 12 to the other pole of the battery B to complete 5 the circuit and for electrically operating both the alarm and torch, as may be required. Both the torch and alarm are preferably controlled electrically from the switch *i*, located in any preferred position in the edifice, for 10 making effective the use of the devices of my said invention. It will be observed from the drawing that the said device as arranged is simple in construction and is adapted to be readily taken apart for repairs or otherwise. 15 5. It will be manifestly obvious that modifications in the manner of the arrangement and mode of igniting the torch and alarm for producing the pyrotechnic signal-alarm and continuing slow-burning torch-light may be 20 made besides the mode and manner of manipulating the same hereinbefore explained, and hence I do not wish to be understood as limiting myself to the particular arrangement illustrated and as hereinbefore explained; but, 25 25. Having thus described the nature and object of my invention, what I claim as new, and desire to secure by Letters Patent, is— 1. A pyrotechnic signal-alarm and burning torch, comprising a standard or support carrying sockets, shells or tubing removably connected with said sockets, ignitable and easily-ignited pyrotechnic materials or substances respectively packed in said shells or tubing adapted to produce slow burning and a pyrotechnic display, fuses in said shells or tubing about said materials or substances, and means 30 suitably mounted in said shells and connected with a source of energy for igniting said sub-

stances or materials, substantially as and for the purposes described. 40

2. A pyrotechnic signal-alarm and burning torch, comprising supported sockets engaged by insulated metal-faced blocks, shells or tubing connected with the metal facing of said blocks, fuse-wires mounted in said shells or 45 tubing and surrounded by substances or materials of respectively ignitable and easily-ignited pyrotechnic properties for producing slow burning and a pyrotechnic display, and electric means connected with the source of 50 energy and with said sockets and fuses for igniting said materials or substances in said shells or tubing, substantially as and for the purposes described. 55

3. A pyrotechnic signal-alarm and burning torch, comprising supported shells or tubing respectively packed with an ignitable and with an easily-ignited pyrotechnic substance or material, one of said shells or tubing having in one portion a readily-ignitable material with a removable cap, while the other is provided with packings and with an easily-ignited pyrotechnic material interposed between the packings, fuse-strips provided with wires mounted in each of said shells or tubing, 60 and means connected with a source of energy and with said supported shells or tubing and fuses, substantially as and for the purposes described. 65

In testimony whereof I have hereunto set 70 my signature in the presence of two subscribing witnesses.

JAMES C. MOORE.
